UNITED STATES PATENT OFFICE.

FRED J. HEIDEMAN, OF DETROIT, MICHIGAN, ASSIGNOR OF NINETY PER CENT TO
THOMAS C. WHITEHEAD, OF RIVER ROUGE, MICHIGAN.

REFRIGERATING APPARATUS.

Application filed September 21, 1925. Serial No. 57,791.

This invention relates to refrigerating apparatus and more particularly to a sensitizer designed to afford a thermal control more responsive to the changes in temperature and 5 consequently effecting a greater efficiency in the operation of the refrigerating apparatus.

The invention has as an object thereof to provide convenient and practical means for charging the thermo-control circuit with a 10 thermo-responsive fluid after the apparatus has been set up ready for operation or after a period of use in cases where the supply of thermo-responsive fluid has become insufficient because of leakage or other causes.

15 The invention has also among its objects to provide a device of this character operable with equal facility, with minor adjustments, in response to thermal variance as well as pressure variance.

20 The invention has also among its objects to simplify, render more efficient, and improve generally devices of this character and the above as well as other objects, advantages, and novel details of construction, will be

25 made more apparent as this description proceeds, especially when considered in connection with the accompanying drawings wherein one illustrative embodiment of the invention is shown and wherein

30 Fig. 1 is a fragmentary sectional view through a refrigerating apparatus with my invention attached thereto,

Fig. 2 is an enlarged sectional view of the device detached,

35 Fig. 3 is an end elevation of the structure shown in Fig. 2, and

Fig. 4 is a sectional view taken on line 4—4 of Fig. 2.

Referring now particularly to the drawings wherein like reference characters indicate like parts, it will be noted that there is 40 illustrated the wall 10 of the refrigerator or like compartment into which a brine or other non-freezing fluid tank 11 is disposed. The tank 11 may be of any suitable design and is shown as provided with the customary expansion coil 12, the outlet end of which is connected to a fitting 13 arranged at the top of tank 11. The refrigerating means flows 45 into the inlet end (not shown) of expansion coil 12, through this coil and out through the end thereof which is connected to fitting 13.

50 The sensitizer forming the subject matter of this invention consists of a casing indi-

cated generally by the reference character 14 55 provided with a base flange 15 by means of which connection is made with the portion 16 of the fitting for the end of tube 12. The casing or shell 14 of the sensitizer is formed with a longitudinal bore 17 which connects 60 with a nipple 18 threaded therein as at 19. A tube 20 connected to the nipple 18 extends through the refrigerator wall and on to the intake port of the compressor. Bore 17 connects with a branch bore or passageway 21, 65 which in turn connects with the fitting 13 at the end of expansion tube 12. With the construction thus far described it will be apparent that the refrigerating medium flowing out through the end of expansion coil 12 has 70 an uninterrupted flow through the sensitizer to the conduit or tube 20 through which it is conducted back to the compressor.

The casing 14 of the sensitizer is formed preferably parallel with and adjacent to the 75 bore 17, with a chamber 22 closed at one end and communicating at the other with a nipple 23 threaded in the casing as at 24 and to which nipple a relatively small gauge tube 25 is connected. This tube preferably runs parallel 80 with and adjacent to tube 20 and also passes outwardly through the wall of the refrigerator. This tube is adapted to be connected to a thermostat or thermal-controlled switch for controlling the compressor motor of the 85 apparatus. While any desired type of thermostat involving a sylphon may be employed I have conventionally illustrated that form of thermostat more fully described and illustrated in my copending application, Serial 90 Number 57,792, filed Sept. 21, 1925. This thermostat consists essentially of a sylphon 26 connected to tube 25 by means of a nipple 27, this sylphon controlling an electric switch 28 through the medium of a switch-operating 95 arm 29 and a plunger 30 controlled directly by the sylphon.

The tubes 20 and 25 which are arranged in parallel proximity to one another as they pass through the refrigerator wall are preferably 100 insulated therefrom by a rubber gland or washer 31 (see particularly Fig. 1).

Communication is provided between bore 17 and chamber 22 by means of a restricted orifice 32 formed in the wall 33 extending between the two. This orifice 32 is adapted to be controlled by a needle valve member 34 threaded into an interiorly threaded projec-

tion 35 on casing 14. This projection is also exteriorly threaded for the reception of a packing nut 36.

In charging the thermo-control circuit the 5 needle valve 34 is backed out sufficiently to open orifice 32 whereupon the compressor or pump is operated to exhaust all the air or other fluids from the thermo-control circuit. By suitable manipulation of the valve of the 10 refrigerating apparatus this may be accomplished while the refrigerant is maintained accumulated in the condenser. After a complete exhaustion of the air from the thermo-control circuit refrigerant from the refrigerant 15 circuit is admitted into the thermo-control circuit by suitably manipulating the valves to permit the refrigerant to flow into the refrigerant circuit. After the thermo-control circuit is fully charged to the desired 20 pressure the orifice 32 which provides for communication between the chamber 22 and the bore 17 of the refrigerant circuit, is closed by means of the needle valve 34 whereupon the refrigerant conducted to the thermo-control 25 circuit is trapped therein. This method of charging the thermo-control circuit is highly efficient and practical as it permits the charging of this thermo-control circuit from the refrigerant already contained 30 in the system and shipped with the apparatus and permits the thermo-control circuit to be fully charged after the entire apparatus has been set up and ready for operation. It eliminates the necessity of having available for 35 use a separate supply of refrigerant or other thermo-responsive fluid and also enables a relatively unskilled attendant to properly condition the apparatus for use. Furthermore, if, after continued use the amount of 40 thermo-responsive fluid in the thermo-control circuit becomes insufficient either because of leakage or other causes it may be recharged from the refrigerant circuit without much interruption to the operation of the refrigerating apparatus.

Great importance is attached to the strategic disposition of the sensitizer which, as will be noted, is arranged on the top of the brine tank 11 at the point where the highest 50 temperature throughout the refrigerator is encountered. In other words, the sensitiser is placed on top of the brine tank at the outlet end of the expansion coil and as a consequence, is subjected to greater changes in 55 temperature and is furthermore disposed at a point where it will be the first to be affected by a rise in temperature and the last to be affected by a fall in temperature. Consequently, the temperature of the refrigerator may be 60 efficiently controlled from this point and the control apparatus made more responsive.

The refrigerating medium or thermo-responsive fluid trapped in the closed portion or chamber 22 of the sensitiser is affected, by 65 induction, by the temperature of the refriger-

erant flowing through bore 17 of the sensitiser and on through tube 20 to the compressor. It is also affected by the temperature of the air surrounding the sensitiser casing as well as by the temperature of the adjacent 70 wall of the brine tank to which it is attached in heat transmitting contact. When the temperature of the refrigerant in bore 17 and consequently the surrounding air and brine tank wall rises to such an extent as to cause 75 an expansion of the fluid contained in chamber 22, a displacement of the column of fluid in tube 25 will occur, which in turn will expand the siphon and operate the thermal-controlled switch in the customary manner. 80 When, however, the temperature of the refrigerant in bore 17 and of the surrounding air and adjacent brine tank wall has dropped the fluid in chamber 22 will contract, permitting a movement of the fluid in tube 25 in 85 a direction away from the siphon whereupon the siphon will collapse and the electric switch controlled thereby will be opened.

If desirable, the sensitiser may be adjusted, by backing out needle valve 34, and thus 90 opening orifice 32, so as to function in response to the pressure in the expansion coil conduit. In this instance chamber 22 is in direct communication with the expansion coil and tube 20 and by suitably adjusting the 95 spring opposing the expanding movement of the siphon the sensitiser will operate to affect the expansion and contraction of the siphon substantially in the same manner as above pointed out. The siphon will then be 100 operated in dependence upon the changes in pressure in the expansion coil, which variances in pressure are dependent upon the temperature of the refrigerating medium.

As mentioned hereinbefore, the point at 105 which the sensitiser is mounted, that is upon the top of the brine tank 11, is extremely advantageous because of the effect upon the sensitiser of the higher temperature at this point in the refrigerator. Furthermore, the association with the refrigerating apparatus of a sensitiser constructed in accordance with this invention eliminates the necessity of arranging the thermostat within the refrigerator upon the brine tank or immediately adjacent 110 thereto, and consequently eliminates the necessity of disposing the electric conduits running from the switch on the thermostat to the compressor motor, through the wall of the refrigerator and to the interior thereof. 115 With the present construction the thermostat is disposed outside the refrigerator and electric wires need not be associated with the refrigerator in any manner whatsoever.

While the tank 11 has been repeatedly referred to as a brine tank and will be so referred to in the claims, it should be understood that in the place of brine various other types of non-freezing fluid may be employed or a boiler or cooling coil may be used without a 120 125 130

tank containing a non-freezing fluid and I therefore do not wish to be limited to the use of brine in the tank 11 or to a tank.

While the invention has been described and illustrated somewhat in detail, it will be readily apparent to those skilled in this particular art that various changes and modifications may be resorted to without departing from the spirit and scope of this invention and to 10 this end reservation is made to make such changes as may come within the purview of the accompanying claims.

What I claim as my invention is:

1. In a refrigerating apparatus, the combination with a brine tank and an expansion coil, of a sensitizer mounted on the top of said tank and arranged adjacent the discharge end of the expansion coil, a pressure responsive device connected to said sensitizer, and adjustable means within the sensitizers adjustable to selectively cause the pressure responsive device to be actuated either directly by the pressure in the expansion coil or indirectly by the temperature thereof.

2. In a refrigerating apparatus, an expansion coil, a sensitizers adjacent the expansion coil, a pressure responsive device controlled by the sensitizers, and means for causing the said sensitizers and pressure responsive device to be selectively operable either indirectly by the temperature or directly by the pressure in the expansion coil.

3. In a refrigerating apparatus, an expansion coil, a sensitizers adjacent the expansion coil, a pressure responsive device controlled by the sensitizers, and a valve in the sensitizers, the said valve being movable to two extreme positions in one of which the sensitizers and the pressure responsive device connected thereto are controlled by the temperature of the expansion coil and in the other of which the sensitizers and the pressure responsive device connected thereto are controlled by the pressure in the expansion coil.

4. In a refrigerating apparatus, a sensitizers comprising a casing having a bore in constant communication with the outlet of the expansion coil of the apparatus, said casing being formed with a chamber connected to a pressure-responsive device and containing a thermo-responsive means, and means to selectively cause the pressure-responsive device to

be actuated either directly by the pressure in the expansion coil or indirectly by the temperature thereof.

5. In a refrigerating apparatus, a compressor, an expansion coil, a sensitizers comprising a casing formed with a parallelly arranged bore and chamber, said bore being connected to the outlet end of the expansion coil and adapted for connection to the intake port of the compressor, said chamber being connected to a pressure-responsive device for controlling the compressor motor switch and containing a thermo-responsive fluid, and means to selectively cause the pressure-responsive device to be actuated either directly by the pressure in the expansion coil or indirectly by the temperature thereof.

6. In a refrigerating apparatus, the combination with an expansion coil, of a sensitizers associated therewith, a pressure-responsive device spaced from the said sensitizers but connected thereto, thermo-responsive means for controlling the fluid pressure within the pressure-responsive device, and means to selectively cause the pressure-responsive device to be actuated either directly by the pressure in the expansion coil or indirectly by the temperature thereof.

7. In a refrigerating apparatus, an expansion coil, a pressure-responsive device, a sensitizers comprising a casing provided with a passage connected to and permitting the discharge therethrough of the refrigerating medium from the coil and provided also with a chamber connected to the pressure-responsive device, and means to selectively cause the pressure-responsive device to be actuated either directly by the pressure in the expansion coil or indirectly by the temperature thereof.

8. In a refrigerating apparatus, the combination with an expansion coil, of a sensitizers connected to the expansion coil, a pressure responsive device connected to said sensitizers, and adjustable means within the sensitizers adjustable to selectively cause the pressure responsive device to be actuated either directly by the pressure in the expansion coil or indirectly by the temperature thereof.

In testimony whereof I affix my signature.

FRED J. HEIDEMAN.
